UNITED STATES PATENT OFFICE

115,797

DESIGN FOR A COMBINED LAVATORY SPOUT, WASTE HANDLE AND ICE-WATER FAUCET

Jean O. Reinecke, Chicago, Ill., assignor to Crane Co., Chicago, Ill., a corporation of Illinois

Application May 20, 1939, Serial No. 85,095

Term of patent 14 years

To all whom it may concern:

Be it known that I, Jean O. Reinecke, a citizen of the United States, residing at Chicago, in the county of Cook and State of Illinois, whose post-office address is 664 North Michigan Avenue, Chicago, Illinois, have invented a new, original, and ornamental Design for a Combined Lavatory Spout, Waste Handle and Ice-Water Faucet, of which the following is a specification, reference being had to the accompanying drawing, forming part thereof.

Fig. 1 is a top plan view of a combined lavatory

spout, waste handle and ice-water faucet embodying my new design.

Fig. 2 is a side elevation thereof.

Fig. 3 is a front elevation thereof looking toward the outlet of the spout.

Fig. 4 is a rear elevation thereof.

I claim:

The ornamental design for a combined lavatory spout, waste handle and ice-water faucet, substantially as shown.

JEAN O. REINECKE.
